UNITED STATES PATENT OFFICE.

HUGH W. SANFORD, OF KNOXVILLE, TENNESSEE.

RAILWAY CAR.

Application filed March 14, 1927. Serial No. 175,186.

My invention relates particularly to mine cars and other cars of any type wherein the frame of the car has side sills and end sills connecting the side sills.

5 For a car of this type, reference is made to Letters Patent of the United States, No. 1,486,547, granted to me March 11, 1924.

The object of this invention is to so modify the structure of that patent as to facilitate varying the elevation of the end sill structure without varying the height of the side sills above the track on which the car is operated. By means of this improvement new cars may easily be fitted for use 10 with cars already in service at a mine and having their coupling members at various elevations.

In the accompanying drawings,

Fig. 1 is a plan of a structure embodying 20 my improvement;

Fig. 2 is an elevation looking at the structure of Fig. 1 toward the upper end of the sheet;

Fig. 3 is an upright section on the line, 25 3—3, of Figs. 1 and 2, looking toward the right;

Fig. 4 is an upright section on the line, 4—4, of Figs. 1 and 3, looking in the direction of the arrow;

30 Fig. 5 is a plan showing a plate metal blank from which is made the body of the end sill;

Fig. 6 is a perspective of said body formed by bending the blank of Fig. 5;

35 Fig. 7 is a perspective of one of the angle members used for joining the side sills and the end sill;

Fig. 8 is a view similar to Fig. 3 with the angle member reversed;

40 Fig. 9 is a perspective showing the angle member reversed;

Fig. 10 is a section similar to Fig. 4 showing a flange or rib added to the lower edge of one of the angle member arms;

45 Fig. 11 is a section similar to Fig. 4, the side sill being of Z-form;

Fig. 12 shows the structure of Fig. 11 inverted;

50 Fig. 13 is a section like Fig. 3, excepting that the steel plate member of the end sill is placed higher than in Fig. 3.

Referring first to Figs. 1 to 7, inclusive,

of the drawings, A, A are the side sills. In the form shown by the drawings, these sills are of channel form with flanges, A¹ and A², 55 directed outward.

B is the steel plate member of the end sill. This has the upright web, B¹, and an upper horizontal flange, B², and a lower horizontal flange, B³. The corners of the flange, B², 60 are cut to make slanting edges, B⁴; and the corners of the lower flange, B³, are similarly cut to make slanting edges, B⁵, (Fig. 6). This member, B, is formed by folding the blank of Fig. 5 along the dotted lines, B⁶. 65 The blank of Fig. 5 is cut from a plate of rolled steel of desired thickness. This member is also provided with holes, as shown by the drawings.

With this member, B, are combined other 70 members to form the complete end sill structure, as described in my said Patent, No. 1,486,547.

In the form shown in the drawings, the plate member, B is long enough to partially overlap the adjacent ends of the side sills. Said plate member and the side sills are joined to each other by means of corner angle members, C, which are unitary castings similar to but structurally different from the 80 angle members of said patent. One of these angle members is shown in perspective in Fig. 7. One arm or blade, C², of each angle member rests against the inner face of the upright web of the adjacent side sill, A, and 85 extends above the sill and is secured to said web by bolts or rivets, R¹, extending through said arm and said web. The drawings show six such rivets. The other arm or blade, C¹, of each angle extends above the adjacent end sill. Along the upper edge of the arm, C², a horizontal rib, C⁴, extends outward over and rests upon the upper edge of the adjacent side sill. This serves to reduce strains on the rivets, R¹. 95

The back face of the upright web of the plate member, B, is placed against the angle member arms, C¹, at the elevation needed to bring the coupling members to the required height.

100 Rivets, R², extend through said arm and said web to join said parts to each other. In the form shown in the drawings, six such rivets are used. But it is to be noted

that, since the arms, C^1 , extend from the lower edge of the side sills upward above the side sills, there is a material range of elevation for placing the plate member, B .

5 The upward extension of the arm, C^2 , adds stability to the upper part of the plate, C^1 .

Let it be noted that the upright web, B^1 , of the plate member need be only sufficiently high to permit ample attachment to the 10 angle member arms, C^1 , and to afford sufficient space between the horizontal flanges, B^2 and B^3 , for the insertion of the coupling and bumper members which are supported by the plate member.

15 The upright web, B^1 , of the plate member, B , is to have holes, R^2 , to receive the rivets, R^2 . The number of such holes may be only the same as the number of rivets, and said holes may be placed in a fixed position regardless of the height at which the plate member is to be placed. In the upright arm, C^1 , of the corner angle member, corresponding holes are to be drilled at a height which will bring the plate, B , to the desired height 20 when the rivets, R^2 , have been inserted.

25 Thus if a lot of cars are made with requirement for placing the coupling structure at a certain height, the holes in said corner angle member are to be drilled as above mentioned to bring the plate member to that height. If the prescribed height of the coupling members is such as to bring the middle horizontal plane of the plate member into the middle horizontal plane of the side 30 sills (the plate member, B , being directly opposite the ends of the side sills), the angle members may be placed on the side sills with the extensions directed either upward or downward. But if that plane of the plate member is to be above that plane of the side 35 sills, the corner members are to be placed on the side sills with the extensions reaching above the sills (Figs. 2, 3, 4 and 13). If that plane of the plate member is to be below that plane of the side sills, the 40 corner members are to be inverted so as to make the extensions reach downward below the side sills (Figs. 8 and 9). As above noted, whatever is to be the elevation of the plate member, the rivet holes in the arms, C^1 , of the angle members are to be 45 drilled at appropriate elevations.

50 Fig. 10 shows the arm, C^2 , of the angle member provided with a rib or flange, C^5 , extending along the lower edge of said arm and overlapping a part of the lower face of the side sill. This flange supplements the action of the rib, C^4 , for reducing strains on the rivets, R^1 .

55 In Fig. 11, the side sill, A^3 , is of Z-form. The upper flange, A^4 , is directed outward and the lower flange, A^5 , is directed inward or toward the opposite side sill. The lower edge of the angle member arm, C^2 , rests on 60 the flange, A^5 , and thus receives support for

tending to diminish strains on the rivets, R^1 . In Fig. 12 this structure of Fig. 11 is inverted.

An inner or second member, D , of strong wood, preferably oak, is placed on the lower 70 flange, B^3 , and against the upright web, B^1 , of the plate member, B . The upper and the lower and the inner faces of the inner wood member, D , are straight, while the outward face nearly conforms to the outer edges of 75 the flanges, B^2 , and B^3 , of the plate member, B , the wood member being extended outward a little beyond said flanges.

Midway between the ends of the end sill an angle-form anchor plate, D^1 , extends 80 across the upper face of the wood member, D , and between said member and the web, B^1 , of the plate member, B , and is secured to said web by rivets (not shown). The horizontal part of this anchor member has 85 a hole, D^2 , to receive the coupling pin to be described further on. A bumper member, E , is curved and of channel-form, having an upright web, E^1 , and an upper flange, E^2 , and a lower flange, E^3 . Said bumper 90 member is placed at the middle of the end sill and has its web, E^1 , bearing against the outer, upright face of the wood member, D , while its upper flange, E^2 , rests on the upper face of the plate, D^1 , and its lower flange, 95 E^3 , extends across the lower face of the flange, B^3 , of the plate member, B . This bumper member is to receive contact or impact from the bumper of another car. The bumper member and the outer part of the 100 wood member form a bumper, the wood being a cushioning member or material against which the bumper member rests.

Thus space for a coupling link is left between the upper face of the bumper member 105 on the one hand and the upper flange, B^2 , of the plate member, B . Upright binding bolts, E^4 , extend through the bumper member and the flange, B^3 , and the wood member, D , and the upper flange, B^2 . Between 110 the bumper member and the upper flange, B^2 , each of said bolts is surrounded by a spacing sleeve, B^5 , whereby the distance between the bumper member and the flange, B^2 , is maintained. Between the bolts, E^4 , and on the middle, longitudinal line of the car is the upright coupling pin, F , extending 115 through the two flanges of the bumper member, E , and the wood member, D , and the hole in the horizontal part of the anchor member, D^1 , and through the upper flange, B^2 , of the plate member, B . Between the upper flange, B^2 , and the flange, E^1 , the pin, F , is surrounded by a spacing sleeve, F^1 , which maintains the distance between said 120 flanges. A coupling link, F^2 , surrounds the bolt, F , and the spacing sleeve, F^1 .

Between the bumper member, E , and the ends of the end sill, bolts, G , extend through 125 the lower flange, B^3 , and the wood member, D .

D, and the upper flange, B². Between the wood member and the web, B², each of said bolts is surrounded by a spacing sleeve, G¹, and between each such spacing sleeve and 5 the wood member is a washer, G².

By means of the various bolts and spacing sleeves and washers, the several members are firmly bound to each other to form the composite end sill described by my patent 10 mentioned above.

It is to be observed that the flanged metal end sill member may be off-set relative to the side sills so as to bring the coupling link, F², above the horizontal plane of the upper 15 faces of the side sills.

When the link is in this elevated position, the car may be coupled to another car having relatively high coupling means, and yet the car of this application may have low 20 side sills and a low bottom, whereby the load is brought close to the level of the track rails. At the same time the flanged metal end sill member is adapted to be placed low enough to bring the coupling link, F², opposite the ends of the side sills; and by inverting the corner angle members and the flanged metal end sill member, the link, F², 25 may be placed lower than the side sills to permit coupling to another car which has 30 equally low coupling means.

It is also to be noted that the coupling pin, F, may be of the ordinary loose form instead of the form having a nut, as shown by the drawings.

35 I claim as my invention:

1. In a railway car, the combination with side sills and angle members, of a flanged metal end sill member formed to present a continuous upright back face to the angle 40 members, and each angle member having an arm over-lapping and secured to the side of the adjacent side sill and having an arm lying against and secured to the back face of the end sill member, the upright dimension of said arm being greater than the height of the side sills, whereby the end sill member may be attached to the angle members at different elevations.

2. In a railway car, the combination with 50 side sills and angle members, of a plate metal end sill member formed to present a continuous upright back face to the angle members and to present upper and lower horizontal flanges free from each other, and 55 each angle member having an arm over-lapping and secured to the side sill and having an arm lying against and secured to the back face of the end sill member, the upright dimension of said arm being greater than the height of the side sills, whereby the end 60 sill member may be attached to the angle members at different elevations.

3. In a railway car, the combination with side sills and angle members, of a flanged

metal end sill member formed to present a 65 continuous upright back face to the angle members, and each angle member having an arm over-lapping and secured to the side of the adjacent side sill and having a rib engaging a horizontal face of the side sill and 70 the angle member having an arm lying against and secured to the back face of the end sill member, the upright dimension of said arm being greater than the height of the side sills, whereby the end sill member 75 may be attached to the angle members at different elevations.

4. In a railway car, the combination with side sills and angle members, of a flanged metal end sill member formed to present a 80 continuous upright back face to the angle members, and each angle member having an arm over-lapping and secured to the inner side of the adjacent side sill and having an arm lying against and secured to the 85 back face of the end sill member, the upright dimension of said arm being greater than the height of the side sills, whereby the end sill member may be attached to the angle members at different elevations. 90

5. In a railway car, the combination with side sills and angle members, of a flanged metal end sill member formed to present a continuous upright back face to the angle members, and each angle member having an arm over-lapping and secured to the side of the adjacent side sill and having a rib engaging a horizontal face of the side sill and the angle members having an arm lying against and secured to the back face of the end sill member, the upright dimension of said arm being greater than the height of the side sills, whereby the end sill member 95 may be attached to the angle members at different elevations. 100

6. In a railway car, the combination with side sills and angle members, of a flanged metal end sill member formed to present a continuous upright back face to the angle members, and each angle member having an arm over-lapping and secured to the side of the adjacent side sill and having an arm lying against and secured to the back face of the end sill member, said arm extending above the side sills, whereby the end sill 110 member may be attached to the angle members at different elevations.

7. In a railway car, the combination with side sills, of a horizontal flanged plate metal end sill member supported by the side sills 120 and having an upper flange forming a part of the coupling means adapted to engage a coupling link, said flange being at a height above the side sills sufficient to allow bringing the coupling link above the horizontal 125 plane of the upper faces of the side sills.

8. In a railway car, the combination with side sills, of a horizontal flanged metal end

- sill member supported by the side sills and having its upper flange forming a part of the coupling means adapted to engage a coupling link, the end sill member being off-
5 set on the side sills to bring its upper flange high enough above the side sills to allow bringing the coupling link above the horizontal plane of the upper faces of the side sills.
- 10 9. In a railway car, the combination with side sills, of an end structure including a flanged plate metal end sill member and means supported by said member for engaging a coupling link, said flanged end sill member being supported on the side sills high enough to allow bringing the link above the horizontal plane of the upper faces of the side sills.
- 15 10. In a railway car, the combination with side sills, of an end structure including a flanged plate metal end sill member and a coupling pin engaged by the flanges of said flanged member having its flanges extending away from the side sills, the upper flange of said flanged member sufficiently high relative to the side sills to allow bringing the coupling link above the horizontal plane of the upper faces of the side sills.
- 20 11. In a railway car, the combination with side sills, of an end structure including a flanged plate metal end sill member having its flanges extending away from the side sills and means supported by said member for engaging a coupling link, said flanged end sill member being supported on the side sills in position to allow bringing the coupling link outside the space enclosed by the horizontal planes of the upper and lower faces of the side sills.
- 25 40 12. In a railway car, the combination with side sills, of an end structure including a flanged metal end sill member having its flanges turned away from the side sills and a coupling pin engaged by the flanges of said flanged member, one of the flanges of said flanged member being at a height relative to the side sills to allow bringing the coupling link above the horizontal plane of the upper faces of the side sills.
- 30 45 13. In a railway car, the combination with side sills and corner angle members secured to and extending above the side sills, of a horizontal flanged metal end sill member supported on the corner angle members, a coupling pin supported by the flanged end sill member, the flanged end sill member being at a height sufficient to allow bringing the coupling link above the horizontal plane of the upper faces of the side sills.
- 35 14. In a railway car, the combination with side sills and corner angle members secured to the side sills, of a horizontal flanged metal end sill member supported on the corner angle members and having its flanges turned away from the side sills, a coupling pin supported by the flanged end sill member, the end sill member being at a height to allow bringing a coupling link outside the space enclosed by the horizontal planes of the upper and lower faces of the side sills.
- 40 15. In a railway car, the combination with side sills and corner angle members, of a reversible flanged metal end sill member having its flanges turned away from the side sills and having one of its flanges forming a part of coupling means adapted to engage a coupling link near said flange, and said end sill member being adapted to be supported on said corner angle members in such position as to bring said coupling link outside the space enclosed by the horizontal planes of the upper and the lower faces of the side sills.
- 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300
